UNITED STATES PATENT OFFICE.

ADAM C. HENDRICKS, OF MARTINSBURG, WEST VIRGINIA.

AUTOMATIC PHONOGRAPH-STOP.

1,327,955.

Specification of Letters Patent. Patented Jan. 13, 1920.

Application filed June 12, 1919. Serial No. 303,589.

To all whom it may concern:

Be it known that I, ADAM C. HENDRICKS, a citizen of the United States, residing at Martinsburg, in the county of Berkeley and State of West Virginia, have invented certain new and useful Improvements in Automatic Phonograph-Stops; and I do declare the following to be a full, clear, and exact description of the invention, such as will enable others skilled in the art to which it appertains to make and use the same.

My invention relates to phonograph stops and more particularly to the type designed for disk instruments and provided with a friction brake for the rotary disk-carrying table; and my principal object is to generally simplify and improve upon the devices shown by my U. S. Patents Nos. 1256317 of February 12, 1918, and 1277583 of September 3rd, 1918.

In carrying out the above end, a further object is to provide a hand wheel for adjusting the stop according to the length of the record, and to obscure practically all other parts from view by said hand wheel, thus necessitating that fewer parts be nickel-plated or otherwise ornamentally finished.

Other objects are to provide a device which is compact, may be inexpensively manufactured and marketed, and may be easily adjusted for playing selections of different lengths, the arrangement being such as to cause stoppage of the rotating table immediately after the last of the record has been played.

With the foregoing in view, the invention resides in novel constructions and arrangements of parts hereinafter fully described and claimed, the descriptive matter being supplemented by the accompanying drawings which form a part of this application.

Figure 1 is a top plan view showing the application of my invention.

Figs. 2 and 3 are vertical sections on the planes indicated by the lines 2—2 and 3—3 of Fig. 1.

Fig. 4 is a horizontal section through the tone arm and the brake flange of the instrument, showing a top plan view of the present invention with the hand wheel removed, this view disclosing the several parts in the relations which they assume when the instrument is in operation.

Fig. 5 is a view similar to Fig. 4 but illus-

trating the relation of parts when the record has been entirely played and the brake is applied.

Fig. 6 is a top plan view of the invention with both the hand wheel and the control arm for the brake actuator removed.

Fig. 7 is a top plan view of the attaching base, and Fig. 8 is a perspective view of such base.

In the drawings above briefly described, I have shown a graphophone including the usual cabinet 1, rotating table 2 and horizontal, swinging tone arm 3, said table being provided with the usual depending brake flange 4, while the tone arm carries the reproducer and needle 5 in the well known manner. I mount a vertical post fixedly on the cabinet 1, provide a brake coacting with the flange 4, equip said brake with an actuator mounted on said post, control the movement of said actuator by the swinging of the arm 3, and provide a hand wheel mounted on said post over said actuator for adjusting the device according to the length of the record, and although I might construct a device of this general character in a great number of ways, I prefer the construction specifically described below.

A horizontal, preferably circular base 6 is attached by two screws 7 and 8 to the cabinet 1 or to any other suitable support, being passed through an eccentric opening 7' in the base and forming a pivot upon which said base may swing for adjustment when it is applied to the instrument. The other screw 8 passes through an arcuate slot 8' in a lateral ear 9 with which the base is provided, and this screw serves to clamp the base against shifting after it has once been adjusted. The base 6 is provided with a recess in its upper side which is preferably formed by constructing a vertical annular flange 10 around the edge of said base, and rising centrally within said recess, is a vertical post 11.

A brake is provided for the table 2, said brake preferably consisting of a friction shoe 12 and an arm 13 carrying said shoe, said arm being pivoted at 14 to a preferably circular brake actuator 15 which is pivotally mounted on the post 11 and rests on the base 6. For properly adjusting the brake to the flange 4, the arm 13 may be moved around the pivot 14 and then held in adjusted posi-

tion by a clamping screw 16 which passes through an arcuate slot 17 in a lateral lug 18, with which the actuator 15 is provided.

The actuator 15 is equipped with a lateral arm 19 which co-acts with a horizontal finger or shoe 20 on the tone arm 3 to normally prevent application of the brake, but the moment the end of the selection is reached, the shoe and arm allow a coiled spring 21 to come into play to rock the actuator and brake in a manner to apply the shoe 12 as seen in Fig. 5. The arm 19 is preferably mounted in opposed slots 22 formed in the upper edge of an annular flange 23, which rises from the actuator 15, and in most cases, I will provide said arm with a slot 23' through which the post 11 rises.

The outer end of the arm 19 forms a preferably curved track 24 upon which the shoe 20 travels when the instrument is playing, but said arm is adjustable with respect to said shoe, in order that the latter may be suddenly received in a notch 25 at the inner end of the track, when the end of the selection is reached. When this relation of parts occurs as seen in Fig. 5, the spring 21 acts to apply the brake and bring the table 2 to a standstill. One wall 26 of the notch 25 is preferably beveled, and the track 24 is provided with a pivoted, spring pressed extension 27 which extends normally beyond said beveled notch wall. When the tone arm is swung by hand to starting position, the shoe 20 pushes against the track extension 27, swings the latter against the tension of its spring 28, and then rides along the bevel 26 onto the track 24 for further operation. This movement of course releases the brake.

For adjusting the arm 19, I provide a hand wheel 29 which is rotatably mounted upon the upper end of the post 11, and this post may well be provided with a nut 30 for holding all parts against removal therefrom, and I preferably provide a metal washer 31 and a yielding washer 32 between said nut and wheel 29, to frictionally hold the latter in any position to which it may be adjusted. In most forms of the invention, I intend to employ an eccentric 33 on the lower side of the wheel 29 and an eccentric strap 34 receiving said eccentric and pivoted at 35 to the arm 19. It will thus be seen that by rotating the hand wheel, the arm 19 may be shifted inwardly or outwardly to adjust the device for operation at the proper time. The wheel 29 preferably carries a scale or the like 36 coöperating with an indicator 37, and this indicator may well be secured in a projecting lug on the actuator 15, by means of a screw 38. For proper adjustment for stopping the device at the end of any record, it may be ascertained at 65 which point on the scale 36, the indicator

37 is then located, and by making the proper notation on the record, the stop device may be set at that particular point each time the record is to be played. It will thus be seen that the brake may be made to come into play exactly at the proper time.

It will be observed that the hand wheel 29 covers and obscures from view all parts except the outer end of the arm 19, the shoe 20, and a small part of the arm 13. It is thus necessary that only a few parts be ornamentally finished by any method such as nickel-plating, and consequently the expense of manufacture is greatly reduced. Furthermore, practically all parts are of such formation as to permit construction thereof by stamping or die casting, and either of these methods is a great asset in manufacture. By die casting the hand wheel 29 for instance, the trouble and expense of otherwise forming its serrated edge, machining its upper surface, and forming the scale 36, is eliminated. This wheel is by preference provided with an opening 39 through which the screws 8, 16 and 38 are accessible, and by this novel feature, although the several sectional parts of the device are hidden from view by the wheel in question, the screws employed are accessible for making any necessary adjustments.

The device is simple and compact, may be easily and inexpensively manufactured and marketed, and will be highly efficient and desirable in every way, and since probably the best results may be obtained from the details disclosed, they may well be followed. I wish it understood, however, that within the scope of the invention as claimed, the device may be embodied in numerous other forms.

I claim:

1. In a graphophone stop for disk instruments, a post and means for rigidly mounting it, a brake for the disk table of the instrument, said brake having a spring operated actuator pivotally mounted on said post, means controlled by movement of the tone arm for holding said actuator against movement until the record has been entirely played, and a hand wheel mounted on said post for adjusting said holding means according to the length of the record, said hand wheel extending over and substantially obscuring said actuator.

2. In a graphophone stop for disk instruments, a post and means for rigidly mounting it, a brake for the disk table of the instrument, said brake having an actuator pivotally mounted on said post, a lateral arm extending from said actuator and slidably carried thereby, means adapted for mounting on the sound arm of the instrument for holding the aforesaid arm against movement until the record has been entirely played, and a hand wheel mounted on said

- post over said actuator for adjusting said arm according to the length of the record.
3. In a graphophone stop for disk instruments, a post and means for rigidly mounting it, a brake for the disk table of the instrument, said brake having an actuator pivotally mounted on said post, a lateral arm extending from said actuator and slidably carried thereby, the outer end of said 10 arm forming a track, a shoe for mounting on the tone arm of the instrument, said shoe being adapted to travel along said track and prevent movement of said arm until the record has been entirely played, and a hand 15 wheel mounted on said post over said brake actuator for sliding said arm to relatively adjust said track and shoe according to the length of the record.
4. In a graphophone stop for disk instruments, a post and means for rigidly mounting it, a brake for the disk table of the instrument, said brake having an actuator pivotally mounted on said post, a lateral arm extending from and slidably carried by said 20 actuator, means adapted for mounting on the tone arm of the instrument for holding the aforesaid arm against movement until the record has been entirely played, a hand wheel mounted on said post over said actuator and having an eccentric on its lower side, and an eccentric strap receiving said eccentric and carried by said arm, whereby turning of said hand wheel will adjust said arm according to the length of the record.
- 35 5. In a graphophone stop for disk instruments, a post and means for rigidly mounting it, a brake for the disk table of the instrument, said brake having an actuator pivotally mounted on said post, said actuator 40 having an upstanding flange around said post provided in its upper edge with opposed notches, an arm slidably received in said notches and having a slot through which said post extends, means adapted for 45 mounting on the tone arm of the instrument for holding said arm against movement until the record has been entirely played, a hand wheel mounted on said post over said actuator, and coacting means on said wheel 50 and arm for adjusting the latter, according to the length of the record.
6. A structure as specified in claim 5, said coacting means being housed within said flange.
- 55 7. In a graphophone stop, a stopping member for the record driving means, a pivotally mounted, spring-operated actuator for said stopping device, a control arm extending from said actuator in a direction 60 transverse to its pivotal axis, the outer end of said control arm having a track extending longitudinally of said arm, a shoe movable along said track while the record is being played, said shoe and track prevent 65 ing movement of said arm and actuator

while said shoe is in engagement with said track, and means for sliding said arm longitudinally to adjust its relation with said shoe according to the length of the record.

8. In a graphophone stop for disk instruments, a brake for the disk table of the instrument, said brake having an actuator pivotally mounted for horizontal movement and provided with a lateral arm whose outer end forms a track, a shoe adapted to be carried by the sound arm of the instrument, said shoe being adapted to travel on said track to prevent operation of said actuator until the record has been entirely played, said arm having a notch at one end of the 70 track provided with a beveled side, said notch being adapted to receive said shoe to allow operation of said actuator, and a spring-pressed extension for said track extending beyond said beveled notch wall and 75 movable to allow said shoe to travel along said beveled wall onto the track when the tone arm is returned to starting position.

9. In a graphophone stop for disk instruments, a base for attachment to the instrument, said base having in its upper side a recess, a post rising from said base in said recess, a brake for the rotary disk table having an actuator mounted pivotally on said post and closing said recess, a spring in said 80 recess for moving said actuator to operative position, an arm extending from said actuator for holding it against the tension of said spring, means adapted for mounting on the tone arm of the instrument to hold said arm 85 against movement until the record has been entirely played, and a hand wheel mounted on said post over said actuator for adjusting said arm according to the length of the record.

10. A structure as specified in claim 9, said base having an opening to receive an attaching and pivot screw and having a lateral lug provided with an arcuate slot for the reception of an additional screw, whereby said base may be adjusted when applied to the instrument.

11. A structure as specified in claim 9, said base having an opening to receive an attaching and pivot screw and having a lateral lug provided with an arcuate slot for the reception of an additional screw, whereby said base may be adjusted when applied to the instrument, said hand wheel having an opening through which said additional 110 screw is accessible when said hand wheel is properly set.

12. A structure as specified in claim 1, said brake including an arm and a screw adjustably securing it to said actuator, said hand wheel having an opening through which said screw is accessible when said wheel is properly set.

13. A structure as specified in claim 1, together with an indicator, a screw securing 130

said indicator to said actuator, and a scale on said hand wheel coacting with said indicator; said hand wheel having an opening through which said screw is accessible when said wheel is properly set.

14. In a graphophone stop for disk instruments, a base adapted for attachment to the instrument cabinet adjacent the record carrying table, said base having in its upper side a recess, a fixed post rising from said base within said recess, a brake actuator pivotally mounted on said post and resting on said base, an adjustable brake carrying arm extending from said brake actuator for stopping the aforesaid table, said actuator having an upstanding annular flange spaced around said post and provided with notches in its upper edge, a sliding arm received in said notches and having a slot through which said post passes, the outer end of said arm forming a track and having a notch at the inner end of said track, a shoe adapted for mounting on the tone arm of the instrument to normally travel along said track and prevent operation of said actuator until said shoe reaches said notch, a spring confined in the recess of said base for then operating said brake actuator to apply the brake, a hand wheel rotatably mounted on the upper end of said post and obscuring said base and actuator from view, and co-acting means on said sliding arm and said

hand wheel for adjusting the former from the latter to vary the relation of said shoe and notch.

15. In a graphophone stop for disk instruments, a base, a spring operated brake actuator mounted on said base brake connected operatively with said actuator, means controlled by the tone arm of the instrument for normally holding said actuator against operation, and a horizontal hand wheel for adjusting said holding means according to the length of the record, said hand wheel extending over said actuator and substantially obscuring the same from view.

16. In a graphophone stop for disk instruments, a base, a spring operated brake actuator mounted on said base brake connected operatively with said actuator, a sliding arm carried by and extending laterally from said actuator, means co-acting with said arm and adapted for mounting on the tone arm of the instrument for holding said actuator against operation while the record is being played, a horizontal hand wheel extending over said actuator, and co-acting means on said wheel and arm for adjusting the latter according to the length of the record.

In testimony whereof I have hereunto set my hand.

ADAM C. HENDRICKS.
